(No Model.)

W. W. GREEN.
METAL BENDING MACHINE.

No. 420,935.

Patented Feb. 11, 1890.

UNITED STATES PATENT OFFICE.

WILLIAM W. GREEN, OF CHICAGO, ILLINOIS.

METAL-BENDING MACHINE.

SPECIFICATION forming part of Letters Patent No. 420,935, dated February 11, 1890.

Application filed November 2, 1888. Serial No. 289,813. (No model.)

To all whom it may concern:

Be it known that I, WILLIAM W. GREEN, a citizen of the United States, residing at Chicago, in the county of Cook and State of Illinois, have invented certain new and useful Improvements in Metal-Bending Machines, of which the following is a full, clear, and exact description, that will enable others to make and use the same, reference being had 5 to the accompanying drawings, forming a part of this specification.

The object of this invention is to provide a machine for bending a strip or flat piece of metal edgewise, as will be hereinafter set forth.

Figure 1 is a plan of a machine embodying my improved features; Fig. 2, a vertical transverse section in plane 2, Fig. 1; Fig. 3, a vertical transverse section in plane 3, Fig. 20 1; Fig. 4, a vertical section in plane 4, Fig. 1.

Referring to the drawings, A represents the bed-frame, upon which the operating mechanism is mounted, and A' the supporting legs.

25 The circular bending or forming die B is rigidly mounted on the pivot-shaft B', journaled in the bed-frame, and turns therewith. The projecting end B² is a part of the bending-die B and moves around with the same.

30 The periphery or outer edge of the die B is cut away from the top down to about one-half its thickness to provide the seating-ledge a. The curved clamping-plate B³ fits into and corresponds to the part cut away to 35 form the ledge a. The bolts a' a³ are loosely inserted through the clamping-plate and have a threaded engagement with the die B, and serve the purpose of retaining the clamping-plate in proper relative position. The inner 40 ends of the rectangular plates a³ a⁴ are bolted to the body of the die B and extend outward over the curved clamping-plate B³, as shown in Fig. 1. The screw clamping-bolts a⁵ a⁶ are threaded in the outer ends of the plates 45 a³ a⁴, and have a bearing on top of the clamping-plate B³, and thereby rigidly clamp and hold the strip of metal B⁴ in the movable die during the operation of bending, as shown in Fig. 2.

50 The stationary die-block C is rigidly secured to the bed-frame, and is curved out

along a part of the inner face, as at b, to correspond to the contour of the movable bending-die. This stationary die-block is provided with the recess b', in which is inserted 55 the strip of metal to be bent, as shown in Fig. 4.

The lower end of the vertical windlass-shaft D is journaled in the bed-frame at the back end, while the upper end is suitably 60 supported in the angle-bracket b², as shown in Figs. 1 and 3. A ring-bolt b³ is inserted in the forming-die at one side, and has one end of the purchase-chain D' attached thereto, the opposite end being attached to the 65 windlass-shaft D, the chain, however, being rove first over the sheave d, then over the guide-roller d', journaled in the bracket d², and back again over the sheave d to the windlass, for the purpose of increasing the purchase and power. The windlass-shaft is provided with one or more apertures d³, for the 70 insertion of the hand-lever F for operating the movable die. The sheave d is journaled on the shaft d⁴.

75 The machine is shown in its normal position, (see Fig. 1) and has a strip of metal inserted ready for the operation of bending.

The plate g is bolted to the projecting end B² of the movable die B, and is provided with 80 one or more clamping-bolts g', for securing and holding the inner end of the strip of metal. By rotating the windlass-shaft the movable die turns on its pivot and the strip of metal is bent into a form corresponding to 85 the periphery of the bending-die.

The machine illustrated is operated by hand; but it is obvious that a very slight change would be required to convert the same 90 into a power machine.

Having thus described my invention, what I claim as new, and desire to secure by Letters Patent, is—

1. In a bending-machine, the combination, with the supporting bed-frame, of a bending-die rigidly mounted and turning on a pivot-shaft and provided with a seating-ledge, as described, a curved clamping-plate adjustably secured on said ledge, and a stationary die-block provided with a recess and rigidly secured to the bed-frame, substantially as and for the purpose set forth.

2. In a metal-bending machine, the combination, with the movable bending-die mounted and turning on a pivot-shaft, of a windlass-shaft journaled in the bed-frame, a purchase-
5 chain, the respective ends whereof are se-
cured to said die and windlass-shaft, the
sheave d , the guide-roller d' , over which said

chain is rove, and the fixed die C, substan-
tially as and for the purpose set forth.

WILLIAM W. GREEN.
